CLAIM

The ornamental design for a mascara shield, as shown and described.

DESCRIPTION

FIG. 1 is a front elevational view of a mascara shield showing my new design, the side opposite being a mirror image of the side showing;

FIG. 2 is a right side elevational view thereof;

FIG. 3 is a left side elevational view thereof;

FIG. 4 is a top plan view thereof; and,

FIG. 5 is a bottom plan view of the mascara shield of my invention.

FIG.1

FIG.5
